CLAIM

The ornamental design for a vehicle fairing, as shown and described.

DESCRIPTION

FIG. 1 depicts a front, top, left perspective view of a vehicle fairing showing my new design.

FIG. 2 depicts a front, right, bottom view thereof;

FIG. 3 depicts a front view thereof;

FIG. 4 depicts a back view thereof;

FIG. 5 depicts a left side view thereof;

FIG. 6 depicts a right side view thereof;

FIG. 7 depicts a top view thereof; and,

FIG. 8 depicts a bottom view thereof.

The ghosted or low contrasted portions of the vehicle fairing illustrate portions that form no part of the claimed design.

1 Claim, 8 Drawing Sheets
